DETACHABLE HANDLE FOR TRUCKS

Ellsworth Y. Mann, North St. Paul, Minn.

Application August 3, 1942, Serial No. 453,490

4 Claims. (Cl. 16—114)

Many of the hand operated trucks in use in industrial and munitions plants are so constructed that permanently attached handles cannot be located where required on the trucks without sacrificing other advantageous features such as compactness and provision for stacking the trucks in telescoped relation to each other. Since such trucks when loaded often weigh more than a thousand pounds, the work of moving them about involves the application of considerable force and experience has shown that due to the lack of adequate handles injury to the operators frequently occurs.

It is an object of this invention to minimize such accidents, without sacrificing other features of construction, by providing strong, readily attachable and detachable handles which may be carried about by the workmen and quickly attached to trucks when required.

A further object is to provide rigid, fixed attaching means for a handle of this class whereby better control of the truck is afforded and all bolts and other small movable fastening members are eliminated.

Other objects will appear and be more fully pointed out in the following specification and claims.

Referring to the drawings:

Figures 1 and 2 are side and end views respectively illustrating one of the common types of hand operated munitions trucks and showing one of my improved handles in place thereon;

Fig. 3 is a perspective view illustrating the same form of my handle;

Fig. 4 illustrates the same handle in front elevation and in place on the truck, a fragmentary corner portion of which is shown;

Fig. 5 is a plan view showing the handle together with a corner portion of the truck;

Fig. 6 is a side view showing an alternate form of my handle in connection with a truck of a common smaller or lower type, and

Fig. 7 is a perspective view of the form of the invention shown in Fig. 6.

Referring to the handle for the larger type of truck shown in Figs. 1 to 5 inclusive, I provide a rigid supporting plate 8 along one edge of which is an integral flange 9 projecting at a right angle. Integral with the plate 8 along its opposite edge is a relatively narrow flange 10 having along its normally lower edge a flange or projection 11 extending back toward the flange 9 to engage beneath a member of a truck, as hereinafter described. Rigidly secured to the top of the plate 8, preferably by welding, is a tubular

grip member 12 which is offset upward from the plate 8 to provide a large inverted U-shaped handle. The ends 13 of this grip member are flattened and bent to extend along and in contact with the plate 8. Projecting longitudinally from the grip member 12 is a rigid ear 14 which is adapted to engage an upright member of the truck to prevent forward tilting of the handle when in use.

10 The truck shown in Figs. 1, 2, 4 and 5 comprises an elevated rectangular box 15 having an open top adapted to receive the load such as loose, small arms, cartridge cases, ammunition or other articles to be transported, supported on a rigid frame and wheels. Extending around the top of the box 15 and projecting outward therefrom is a rigid flange 16 which affords a supporting member for the handle. The truck frame includes angle bars 17 projecting upward from the four corners of the box 15 and other suitable frame members such as the horizontal members 18 on which the wheels 19 and 20 are mounted.

20 My improved handle is formed to fit on the flange 16 with the pendant flange 9 extending inside of the box 15 along the inner wall thereof and with the opposite flange 10 engaging the outer edge of the flange 16. When in place on the truck the ear 14 extends in contact with the rear or inner surface of one of the angle bars 17, so that the handle cannot be tilted outward, and the flanges 9 and 10 transmit propelling forces to the front and rear edges of the flange 16 while the flange 11 prevents upward withdrawal of the handle and inward tilting of the plate 8. To detach the handle it is only necessary to slide it along the flange 16 until the ear 14 has been withdrawn from behind the angle bar 17 and then to tilt the handle outward, as indicated in dotted lines in Figs. 1, 4 and 5 followed by raising of the flanges 9, 10 and 11 out of engagement with the edges and lower surface of the flange 16. The flange 11 fits the outer edge of the flange 16 loosely enough to permit the necessary tilting of the plate 8. It will be readily understood that the handle may be attached to the truck by reversing the tilting and sliding operation described.

25 In the alternate form of my device, shown in Figs. 6 and 7, I provide an attaching bracket having a top plate 21 formed with a pendant flange 22 along one edge, a shorter flange 23 along the other edge and a reentrant flange 24 along the lower edge of the flange 23. Rigidly fastened to the top of the plate 21, preferably by welding, is

a stout rod or tongue 25 formed with a closed loop handle 26 at its normally forward and upper extremity. The truck shown in Fig. 6 is of the low type having a sheet metal body 27 which is open at its top and provided with a horizontally and outwardly projecting flange 28 around its upper edge. This truck is supported on pairs of wheels 29 and 30.

The flange 22 of the handle fits inside of the body 27 and the flanges 23 and 24 engage the outer edge and beneath the flange 28 of the truck when the tongue 25 is in the normal, elevated position shown in full lines in Fig. 6. Force for moving the truck is transmitted through the plate 21 and flanges 22, 23 and 24 so that the truck may be propelled to the front or rear and its lateral movement controlled. To detach the handle, the tongue 25 is depressed, as indicated in dotted lines in Fig. 6, and then merely withdrawn obliquely upward and to the front. The device may be attached by reversing the operation described, as in the case of the shorter handle shown in Figs. 1 to 5 inclusive.

Experience has shown that the use of my detachable handles materially reduces the number of accidents which have heretofore been caused by inadequate handles and that the work of propelling and accurately controlling the trucks is facilitated.

Having described my invention, what I claim as new and desire to protect by Letters Patent is:

1. In combination with a truck having a horizontally extending member, a wall depending from said member and a frame member extending upward from said horizontal member, a detachable handle comprising a plate adapted to extend along the top of said horizontal member, a pendant flange extending along an edge of said plate to engage one edge of said horizontal member, a second flange extending along the opposite edge of said plate to engage the opposite edge of said horizontal member, a projection formed on said second flange to engage beneath said horizontal member, a grip member rigidly connected to said plate, said plate, flanges and projection being movable into engagement with said horizontal member by tilting said plate laterally and a lug projecting from said handle for engagement with said truck frame member, the handle being movable longitudinally of said hori-

zontal member to engage said lug with said frame member.

2. In combination with a truck having a horizontally extending member and a wall depending from one edge of said member, a detachable handle comprising a rigid bar adapted to extend along the top of said member, a grip member connected to said bar, a flange depending from one edge of said bar for engagement with said wall of the truck and a hook-shaped flange depending from the opposite edge of said bar to engage an edge and the bottom surface of said member, said flanges fitting said horizontally extending member and wall loosely to permit free tilting of the bar for quick and easy attachment and detachment of the handle.

3. In combination with a manually operable truck having a rigid, horizontally extending end member, at least one longitudinal edge of which is accessible, a readily detachable handle comprising, a rigid bar of substantially L shape in cross section adapted to extend along and engage two of the faces of said end member, a grip member secured to said bar and a hook shaped projection on said bar to engage said edge of the end member, said bar fitting the end member loosely and being freely tiltable, with said edge of the end member as a fulcrum, from operative position laterally in one direction relative to said end member to permit ready removal of the handle from the truck and being confined against tilting in the opposite direction by said projection when the latter is in engagement with said edge of the end member.

4. In combination with a truck having a rigid end structure of substantially L shape in cross section, at least one longitudinal edge of which is accessible, a detachable handle comprising, a rigid bar of substantially L shape in cross section adapted to extend along and embrace two of the faces of said structure, a grip member connected to said bar and a rigid projection on an edge of said bar for engagement with said edge of said end structure, said bar and projection fitting said structure loosely to permit free lateral oscillating movement of the bar in one direction with said edge of the end structure as a fulcrum for quick and easy attachment and detachment of the handle.

ELLSWORTH Y. MANN.
